Primary Examiner — Richard Kearney*Assistant Examiner* — Anthony Vincent Rotolo(74) *Attorney, Agent, or Firm* — Mohr Intellectual Property Law Solutions, PC(57) **CLAIM**

I claim the ornamental design for a lamp shade, as shown and described.

DESCRIPTION

FIG. 1 is a perspective view of a lamp shade supported on a base.

FIG. 2 is a front elevation view thereof.

FIG. 3 is a rear elevation view thereof.

FIG. 4 is a top plan view thereof.

FIG. 5 is a bottom plan view thereof.

FIG. 6 is a right-side elevation view thereof; and,

FIG. 7 is a left-side elevation view thereof.

Broken lines in the drawings illustrate portions of the lamp shade that form no part of the claimed design.
